UNITED STATES PATENT OFFICE.

OTTO KONIGSLOW, OF CLEVELAND, OHIO, ASSIGNOR TO THE OTTO KONIGSLOW MANUFACTURING COMPANY, OF CLEVELAND, OHIO, A CORPORATION OF OHIO.

HINGE.

1,309,579.

Specification of Letters Patent.

Patented July 8, 1919.

Application filed September 7, 1915. Serial No. 49,362.

To all whom it may concern:

Be it known that I, OTTO KONIGSLOW, a citizen of United States, residing at Cleveland, in the county of Cuyahoga and State of Ohio, have invented certain new and useful Improvements in Hinges, of which the following is a specification.

This invention relates generally to hinges and particularly to double hinges utilized for vehicle doors.

More specifically the invention relates to a double hinge structure comprising two mating pin and socket members, of which the socket member is provided with a pair 15 of sockets, each having openings in its side walls to receive a pivot pin, while the pin member has bracket portions extending into the sockets and engaging pins, the main strap portions, together with the brackets of 20 the pin member, being formed from a single piece of sheet metal. The invention also relates to means extending to the outside of the strap of the socket member for withdrawing the pins.

The invention may be further briefly summarized as consisting in the construction and combination of parts hereinafter set forth in the following description, drawings and claims.

Referring to drawings Figure 1 shows a side elevation of the device as applied with the members of the hinge in closed position; Fig. 2 is a view in elevation with the parts open and looking toward the outer face of 35 the strap of the socket member; Fig. 3 is a top plan view with the members of the hinge in closed position; Fig. 4 is a sectional view through the hinge and the adjacent parts taken on a horizontal plane cutting one of 40 the hinge brackets and the corresponding socket; Fig. 5 is a similar view showing the hinge open; Fig. 6 is a plan view of the blank from which the pin member is formed after being blanked out and pierced; Fig. 7 45 is a view of the blank showing the end portions bent over to form the body portions of the brackets; Fig. 8 is a view looking at the outside face of the strap of the pin member; Fig. 9 is an edge view of a portion of one of 50 the straps with the bracket attached, but before having its end bent into a plane parallel with the strap; and Fig. 10 is a similar view showing the end of the bracket bent around in place.

The invention having been described with

respect to the figure of the drawings, a complete detailed description will now be given of the detailed structure set forth in the said figures.

In the drawings 1 represents the main strap of the socket member provided near each end thereof with U-shaped sockets 2 extending transversely across the strap. The U-shaped sockets are adapted to receive the brackets of the pin member as will appear, 60 and in the side walls and near the bottom thereof are suitable openings 3 for receiving the pivot pin 4. The pivot pin of each hinge portion is secured to a clip 5 having an upturning portion 6 extending outward along 70 the inner face of the strap 1. At the end the portion 6 is provided with an outwardly extending T-shaped guiding portion 7 adapted to pass through a suitable slot 8 in the strap 1, the T-shaped head engaging on the 75 outside of the strap and serving to guide the clip in its movement. The clip is held in position with its pivot pin in place by means of a screw 9 passing through the slot and into the clip, the head of the screw being on 80 the outside of the strap 1.

It will be seen from the foregoing that when the socket member is in place and the part to which it is applied is properly mortised, the operator may remove the pin by 85 loosening the screw 9 and moving the clip with the pin until the latter is free.

Suitable stops are formed on the socket member for the pin member and they comprise in each instance a pair of lugs 10 extending inward from the sides of each socket and across the end thereof.

The pin member of the hinge, with its brackets and other parts, is formed from a single piece of sheet metal and since the 95 structure of this pin member forms a part of the invention, it will be described step by step as it is produced from the blank. The blank comprises a main body strap portion 11 having at the ends thereof bracket blank 100 portions 12 extending outward in opposite directions from the main body portions. Each of these bracket blank portions is provided with perforated ears 13 extending diagonally from the bracket blank portions as shown in Fig. 6. Integral with each of the bracket blank portions is an end strap portion 14 spaced from the main body strap 11 by a slot 15 but extending inward toward the center of the piece. This blank is then 105 110

formed so that the bracket blanks are folded into U-shape in cross section, whereby the two ears 13 aline with each other as is clearly shown in Fig. 7, this operation bringing the 5 end strap portions 14 into a position so that they are in parallel alinement with, but are spaced from, the main body strap. The brackets at this stage are then formed so that they extend at right-angles to the main body 10 strap 11, as shown in Fig. 9, and the end strap portions 14 are bent upward so that they are in the plane with the main body strap whereby the piece at this stage represents the structure shown in Figs. 8 and 9. 15 The piece is then formed so that the ends of the brackets are bent around at the center, so that they, with the strap, are substantially U-shaped in cross section as shown in Figs. 3, 4 and 5. The holes in the ears 13 are then 20 bored or reamed to receive the pin 4.

From the foregoing it will be seen that the pin member comprises a strap and hinge brackets formed from a single piece of sheet metal with the accompanying advantages of 25 strength and lightness.

Having described my invention, I claim:—

1. A hinge, comprising a socket member 30 having a hinge socket, a pin member having a hinge bracket, a pin arranged in the socket 35 of the socket member and engaging the bracket of the pin member, a clip secured to the pin and having a portion extending along the inner portion of the socket member, an extension carried by said clip and extending through a slot in said socket member, and a screw passing through the slot

in said socket member and engaging in the clip.

2. A blank for the pin member of a hinge, 40 comprising a main strap portion, bracket blanks formed integral therewith and extending longitudinally from each end thereof, pin receiving ears extending oppositely from the outer end of each bracket blank, 45 and end strap portions extending toward each other inward from the bracket blanks and separated by a slot from the main strap portion and lying in the same plane therewith. 50

3. A hinge pin member formed from a single blank of sheet metal and consisting of a main strap portion, bracket blanks formed integral therewith and extending longitudinally from each end thereof, pin receiving ears extending oppositely from the outer end of each bracket blank, and end strap portions 55 extending toward each other from the bracket blanks and separated by a slot from the main strap portion and lying in the same plane, and comprising a strap including the main strap portion and the end strap portions arranged in the same plane and in longitudinal alinement, and hinge brackets of U-shape in cross section extending at right 60 angles thereto and connecting the main strap portion with the end strap portions. 65

In testimony whereof I affix my signature in presence of two witnesses as follows:

OTTO KONIGSLOW.
